Inventor:

Alfred E. Brumwell
by Franklin H. Longh

UNITED STATES PATENT OFFICE.

ALFRED E. BRUMWELL, OF HURON, SOUTH DAKOTA.

POTATO-PLANTER.

SPECIFICATION forming part of Letters Patent No. 429,498, dated June 3, 1890.

Application filed January 31, 1890. Serial No. 338,732. (No model.)

To all whom it may concern:

Be it known that I, ALFRED E. BRUMWELL, a citizen of the United States, residing at Huron, in the county of Beadle and State of 5 South Dakota, have invented certain new and useful Improvements in Potato-Planters; and I do declare the following to be a full, clear, and exact description of the invention, such as will enable others skilled in the art to which it 10 appertains to make and use the same, reference being had to the accompanying drawings, and to the letters of reference marked thereon, which form a part of this specification. 15 This invention relates to certain new and useful improvements in potato-planters; and it has for its object to improve upon the construction and at the same time to render more durable and efficient in operation this 20 class of machines.

To these ends and to such others as the invention may pertain the same consists in the peculiarities of construction and in the novel combination, arrangement, and adaptation of 25 parts, all as more fully hereinafter described, shown in the accompanying drawings, and then specifically defined in the appended claims.

Like letters of reference indicate like parts 30 in both views, in which—

Figure 1 is a perspective view of a potato-planter constructed in accordance with my invention. Fig. 2 is a central vertical section of the same, in which view the box and its at- 35 tachments are shown as raised.

Reference now being had to the details of the drawings by letter, A represents the axle, B the wheels, and C the pole, of the machine.

D D are brace-timbers, which connect the 40 pole with the axle upon either side and serve to form the main frame of the machine.

E is the driver's seat, which is carried upon the inclined standard E', which rises from the brace-timber D near the point at which said 45 timber joins the axle.

F is a timber the front end of which is provided with a surrounding metallic casing F', having downwardly-extended ears or projections F², adapted to embrace between them 50 the pole C at the point at which it is joined by the brace-timbers D, and said casing is se-

cured to the pole by means of a transverse pivot or bolt F³, passed through said casing and pole.

The timber F extends rearwardly over the 55 longitudinal center of the machine, and its free end projects for a considerable distance to the rear of the axle, as shown.

G is the storage-box for potatoes. This box is secured to the upper face of the timber F, 60 immediately to the rear of the axle, and the rear wall of the box is cut away, as shown.

G' is the seat, which is designed to be occupied by the operator when the machine is in use. This seat is secured to the extreme 65 rear end of the timber F, and is a short distance to the rear of the storage-box.

H H are strips of metal, the lower ends of which are secured to opposite sides of the pole C, a short distance to the rear of the 70 driver's seat. These strips extend vertically upon either side of the timber F, the said timber being capable of free vertical movement between the strips, but secured by them against lateral movement.

I is an angular lever, which is pivoted at 75 its angle between the upper ends of the strips H, the long arm I' of the lever being adjacent to the driver's seat, while the short arm H² of the lever is attached to the timber F by 80 the link H³.

J is a metallic arch, which rises from the axle at a point directly in advance of the storage-box, and the timber F is adapted to be moved vertically within this arch. 85

The arch J is provided with a series of holes I² for the reception of the pin I³, which pin serves to retain the timber F in its adjusted position, as will presently appear.

K is the plow or shoe, which consists of two 90 strips of sheet metal secured at their upper ends to opposite sides of the timber F near its front end, and from their point of attachment with the timber they extend downwardly and rearwardly. Uniting at a point 95 a short distance below the pole C, they together form the body of the plow, and at the extreme rear end, which is directly beneath the rear portion of the storage-box, the strips separate, and between the bifurcations 100 formed by this separation of the strips is received the lower end of the dropper pipe or

tube L, the upper end of which pipe is passed through the bottom of the storage-chamber and is provided with a suitable hopper L'.

M is the covering-wheel, which is journaled within the bracket M', which extends rearwardly from the vertical brace-timber or metallic strip M². This covering-wheel is provided at its sides with the inclined flanges M³, which serve to press the earth inwardly, as will be readily understood.

In operation the pin I³ is removed from its hole in the arch J, and the rear end of the timber F is lowered and the pin is placed again in a hole in the arch through or above the timber F. As the machine is moved forward, the attendant who occupies the rear seat drops the potatoes at intervals through the hopper and pipe L and L' into the furrow that is formed by the plow, and the covering-wheel at once covers and firmly presses the earth in place. When the end of the row has been reached and it is designed to turn the machine, the attendant leaves his seat and removes the pin I³ from the arch J, when the driver, by forcing downward the lever I, raises the rear end of the timber F, together with the rear end of the plow that is attached thereto, and the pin is placed within a hole in the arch through or beneath the timber, thus holding the parts in their adjusted position, with the plow free from the ground, in readiness to resume planting, when the plow may be again lowered, as will be readily understood.

Having thus described my invention, what I claim to be new, and desire to secure by Letters Patent, is—

1. In a potato-planter, the combination, with the frame, the pole, axle, and wheels, of

the longitudinal timber F, the metallic casing F' on the forward end of said timber and having ears pivotally connected to the pole, the seed-box on the rear end of the timber, the dropper-tube leading from the seed-box and having a hopper within the seed-box, the guide-strip H on the pole embracing the timber F, the arch J on the axle and embracing the timber and provided with a plurality of holes, the removable pin, and the angular lever fulcrumed at the upper ends of the strips H and connected with the timber F beneath the arch J, substantially as and for the purpose set forth.

2. In a potato-planter, the combination, with the frame, the pole, axle, and wheels, of the longitudinal timber F, the metallic casing F' on the forward end of said timber and having ears pivotally connected to the pole, the seed-box on the rear end of the timber, the dropper-tube leading from the seed-box and having a hopper within the seed-box, the guide-strip H on the pole embracing the timber F, the arch J on the axle and embracing the timber and provided with a plurality of holes, the removable pin, and the angular lever fulcrumed at the upper ends of the strips H and connected with the timber F beneath the arch J, substantially as and for the purpose set forth.

In testimony whereof I affix my signature in presence of two witnesses.

ALFRED E. BRUMWELL.
